UNITED STATES PATENT OFFICE.

ERNEST E. GOWELL, OF SOUTH PORTLAND, MAINE, ASSIGNOR TO THE E. T. BURROWES COMPANY, OF PORTLAND, MAINE, A CORPORATION OF MAINE.

FOLDING TABLE.

Application filed October 16, 1925. Serial No. 62,892.

This invention relates to improvements in light folding tables of the kind employed for card tables and similar purposes.

One object of the invention is to provide improved leg bracing means of a simple, efficient nature providing for bracing the leg transversely of their pivots and laterally at right angles to their pivotal planes while at the same time permitting of the use of a relatively small size top and top supporting frame, and providing for the compact folding of the legs within the frame substantially parallel with and close in alongside the sides thereof.

15 A further object of the invention is to provide improved top supporting and reinforcing means whereby a simple, strong, rigid construction is afforded.

The invention, with other objects and advantages thereof, and the particular construction, combination and arrangement of parts comprising the same, will be understood from the hereinafter contained detail description, when considered in connection with the accompanying drawings, forming part hereof, and illustrating one embodiment of the invention.

In the drawings:

Figure 1 is a bottom plan view of a table equipped with leg bracing means in accordance with the present invention, the legs being in folded position.

Fig. 2 is a side elevation, the legs being unfolded.

35 Fig. 3 is a detail section on the line 3—3 of Figure 1, a portion of one of the legs unfolded, one of its braces, and one of the brackets being shown in elevation.

40 Fig. 4 is a detail section similar to Figure 3 with the leg portion and brace in folded position.

Fig. 5 is a detail perspective view of one of the brackets.

45 Fig. 6 is a detail view on an enlarged scale, partly in section and partly in side elevation showing the end portion of one of the braces in unfolded position engaging the locking recess of one of the guides.

50 Fig. 7 is a detail section, on an enlarged scale, on the line 7—7 of Figure 1.

Fig. 8 is a detail section, on an enlarged scale, taken on the line 8—8 of Figure 12 looking in the direction of the arrow.

55 Fig. 9 is a detail view, on an enlarged scale, partly in section and partly in side elevation

of a portion of the table top, a part of one of the legs in unfolded position, and parts directly associated therewith.

Fig. 10 is a transverse section on the line 10—10 of Fig. 12 looking in the direction of the arrow.

Fig. 11 is a detail side elevation, with parts shown in section, of one of the legs and one of its braces, the legs being shown in nearly closed or folded position.

65 Fig. 12 is a detail part section and plan of a portion of the table and one of the legs, the legs being shown in folded position.

Fig. 13 is a detail section on the line 13—13 of Figure 12.

70 Fig. 14 is a detail perspective of one of the bracket members for connecting the pivot members of the legs to the reinforcing strips.

While a specific embodiment of the invention is illustrated in the drawings, it will of course be understood that minor changes and variations may be made in the particular construction shown, and the invention embodied in other forms, as will appeal to those skilled in the art and falling within the scope of the appended claims, without departing from the spirit of the invention.

Referring in detail to the particular embodiment of the invention illustrated in the drawings, 1 designates a square shaped top supporting frame composed of bars suitably secured together at their ends, and 2 a relatively light thin top of paper board or the like secured to the top supporting frame in any suitable way. The legs 3 are pivoted to the top supporting frame 1 adjacent the corner portion thereof to fold against the top within the supporting frame substantially parallel with and close to the sides thereof, as illustrated in Figure 1 of the drawings, the legs 3 being pivotally connected by members 4 extending through the sides of the frame 1. 4' designates reinforcing strips for the top 2 secured thereto at the under side thereof in any suitable way, as by gluing.

5 designates braces for the legs 3 adapted to brace the same laterally at substantially right angles to their pivotal planes, each brace 5 being connected at one end to one of the legs 3, extending laterally therefrom at an inclination, and being pivotally connected at its other end to the top supporting frame 1 in line with the pivot of the leg a substantial distance to one side thereof inwardly of the position of the legs when folded. In ac-

100

105

110

cordance with the present invention the braces 5 are connected with the top supporting frame 1 by bracket members 6, each comprising a flat plate portion 6^a secured to a side of the top supporting frame 1 against the inner face thereof, and a flat part 6^b extending inwardly from the portion 6^a at right angles thereto substantially parallel with and adjacent the under side of the top 2 to a point well within the position of the legs when folded, said part 6^b of the bracket having a depending portion 6^c disposed in line with the pivot of one of the legs 3 in a plane at right angles to the portion 6^a of the bracket and to which the upper end of one of the braces 5 is pivotally connected by a pin 6^d. In the particular construction of bracket shown, each bracket 6 is formed from a flat strip of metal bent intermediate its ends at 6^a at the juncture of the portion 6^a and the part 6^b. The part 6^b near its inner end is slotted transversely at 8, and the portion at one side of the slit 8 is bent back to form the depending portion or attaching ear 6^c. The braces 5 are formed from heavy wire, said braces and the portions 6^c of the brackets being capable of being bent slightly, if necessary, to true up the position of the legs when in unfolded position.

30 In conjunction with the lateral braces 5, braces 9 are provided for bracing the legs 3 transversely of their pivots, each of said braces 9 being pivotally connected at one end to one of the legs 3 and having a pivotal sliding connection at its other end with one of the bars of the top supporting frame 1. The braces 9 each consist of a spring rod having an inwardly offset portion 9^a at one end pivotally connected with one of the legs 3, and having an outwardly projecting portion 9^b at its opposite end adapted to engage a guide on the top supporting frame 1. The inwardly offset portion 9^a of the braces, in the particular construction shown, also constitutes the connecting means for one of the cooperating braces 5 with the legs, said inwardly offset portion 9^a at its outer end projecting beyond the outer face of the legs and extending through an opening in the lower end of one of the braces 5 and having retaining means 9^c at its outer end, the outer end portion of the inwardly offset portion 9^a, in this instance, being upset to provide a head or enlarged part for this purpose. The top supporting frame is provided with guides for the leg braces 9, each guide having a longitudinal groove 10 for the lateral extension 9^b of the brace, and an inner longitudinal retaining channel 11 extending at right angles to and adjoining the groove 10, and the lateral extensions 9^b of the braces 9 are each provided with a retaining shouldered or offset end part 12 to slidably engage in the inner longitudinal channel 11 of the guide and cooperate therewith to maintain the lateral extensions 9^b of the braces in engagement with the guide groove 10. The guides are each provided with an opening 13 extending laterally from the outer face thereof to its inner retaining channel 11, said opening 13 being of greater width than the width of the guide groove 10 of a size sufficient to permit of the ready withdrawal from and insertion of the retaining shoulder or offset end portion 12 of the lateral extension 9^b of the brace into the inner channel 11 through said opening in order to adjust the spring tension of the brace or for other purposes. The opening 13 of the guide is located near one end portion of the same so that the shoulder or offset end part 12 of the lateral extension 9^b of the brace will occupy a position opposite the opening 13 when the leg 3 has been moved to nearly closed position, as illustrated in Figure 11 of the drawings, and is disposed at an angle to the guide so that the same does not interfere with the grasping of the end of the brace end by the fingers and the movement of the brace end laterally out of or into engagement with the inner channel 11. In the particular exemplification illustrated in the drawings, the guides are formed by longitudinal recesses in the bars of the supporting frame 1, and metal plates 15 secured to the frame bars adjacent the recesses, said plates 15 projecting above the lower walls of said recesses partially thereover, and the upper edges of the plates 15 extending below the upper wall of said recesses in spaced relation therewith. The retaining shoulder or offset end part 12 of each brace is conveniently formed by recessing or slotting the lateral extension 9^b at 16 at one side thereof intermediate its ends, as shown.

35 The guides, near one end, are each provided in the rear wall thereof with a recess 17 adapted to receive and retain the outer end of the lateral projecting portion 9^b of the brace when the leg is moved to its unfolded position, the end of the outwardly projecting portion 9^b springing into the recess 17 at the end of the opening movement of the leg. The plates 15 extend well beyond the location of the recess 17 along the inner channels 11, said plates 15 serving as stops to limit the outward movement of the lateral extensions 9^b of the braces in disengaging the same from said recesses.

40 The braces 9 are formed of heavy spring wire or spring rods and are transversely resilient, said braces being bent or bowed intermediate their ends, as shown, so that through their transverse resiliency, the opposite end portions of the braces tend to spring outwardly in opposite directions exerting pressure laterally at their ends against the legs and guides on the top supporting frame 1. Said braces 9 serve to hold the legs in folded position, and to hold the legs firm and rigid when in open position. The braces 9 also through their lateral resiliency and the

45 50 55 60 65 70 75 80 85 90 95 100 105 110 115 120 125 130

pressure exerted thereby laterally against the legs serve to take up any lost motion due to possible looseness in the connections of both sets of braces to the legs and the connections 5 of the latter to the top supporting frame, thus insuring an efficient cooperation between the transverse and lateral braces in firmly bracing the legs.

By the special double bracing means for 10 the legs, hereinbefore described, the legs are firmly braced laterally of their pivots as well as transversely thereof, while at the same time the arrangement is such as to permit the use of a relatively small size top and the 15 closing of the full length legs within the top supporting frame substantially parallel with and close in along the sides thereof.

The special construction of bracket, hereinbefore set forth, for connecting the braces 20 to the top supporting frame 1 inwardly of the position occupied by the legs when folded, affords means of an efficient nature for this purpose, the resulting structure being simple, strong, durable and compact, and the 25 parts can be conveniently and quickly assembled and replaced. The special bracket structure provides a firm anchorage for the brace rods 6 to the top supporting frame 1, and the particular bracket and brace structure 30 is also advantageous in that either the braces or the connecting brackets can be bent to correct slight inaccuracies and true up the position of the legs when in unfolded position.

35 It will also be observed that the particular form of transverse brace cooperates in a special manner with the lateral brace to obtain an efficient double bracing of the legs, the lateral braces also while acting to maintain their 40 lateral extensions in engagement with the guides throughout the greater part of the opening and closing movement of the legs, permitting of the convenient manual withdrawal of the brace end from the guide 45 groove for the purpose of adjusting the spring tension of the brace rod or for other purposes.

Means is provided for forming a supporting connection between the inner ends of the 50 pivot members 4 of the legs, the reinforcing strip 4', and the supporting frame whereby the structure is materially strengthened. The pivot members 4 which are in the form of bolts or pins, each having an outer head 4^a 55 to engage an outer face of the frame, are, as shown, of a length to extend through the pivot openings of the legs and project a sufficient distance to the outer sides thereof to provide for the engagement therewith of 60 bracket members. Each bracket member comprises angularly disposed portions or legs 18, 19, the portion 18 being apertured at 65 to fit over an end portion of one of the pivot members 4, and the other portion or leg 19 of the bracket being disposed to inter-

engage with a recessed end portion 21 of one of the reinforcing strips 4. 22 designates washers interposed between the portions 18 of the brackets and the sides of the legs 3, the parts being secured close together on the 70 pivot members 4 in any suitable manner, for instance, by upsetting the inner ends 4^b of the pivot members 4, as shown.

What I claim is:

1. A table including a top, a rectangular frame for supporting the top, legs pivoted to the frame adjacent the corners thereof to fold within the same one alongside each side thereof, braces for the legs, and a bracket member for each brace, each bracket member comprising an end portion adapted to be secured to a side of the frame against the inner face thereof, and a part extending at an angle to said end portion inwardly of the position of the legs when folded, each brace being connected with one of the legs and to said part of one of the bracket members at a point inwardly of the position of the legs when folded. 80

2. A table including a top, a rectangular frame for supporting the top, legs pivoted to the frame adjacent the corners thereof to fold within the same one alongside each side thereof, braces for the legs, and a bracket member for each brace, each bracket member comprising a flat plate portion secured to a side of the frame against the inner face thereof, and a flat plate part extending at an angle to said first mentioned portion and provided with a depending portion disposed inwardly of the position of the legs when folded, each brace member being connected with one of the legs and to the inner depending portion of one of the brackets. 90

3. A table including a top, a rectangular frame for supporting the top, legs pivoted to the frame adjacent the corners thereof to fold within the same one alongside each side thereof, braces for the legs, and a bracket member for each brace, each bracket member comprising a flat plate portion secured to a side of the frame against the inner face thereof, and a flat plate part extending at an angle to said first mentioned portion substantially parallel with and adjacent the under face of the top, said last mentioned part being provided with a depending portion disposed inwardly of the position of the legs when folded, each brace member being connected with one of the legs and to the inner depending portion of one of the brackets. 100

4. A table including a top, a rectangular frame for supporting the top, legs pivoted adjacent the corners of the frame to fold within the same alongside the sides thereof, braces for the legs, and a bracket member for each brace, each bracket member comprising a metal strip bent intermediate its ends to provide an end portion secured to a side of the frame against the inner face thereof, and 115 120 125 130

- a part extending at an angle to said end portion inwardly of the position of the legs when folded, said last mentioned part being provided with a lateral slit near its inner end,
- 5 and a portion of the end portion of said part being bent back to extend downwardly therefrom at a point inwardly of the legs when folded, each brace being connected with one of the legs and with one of the downwardly
- 10 extending portions at the inner end of one of the brackets.
5. A table including a top, a rectangular frame for supporting the top, legs pivoted to the frame adjacent the corners thereof to
- 15 fold within the same one alongside each side thereof, braces for the legs, and a bracket member for each brace, each bracket comprising a flat plate portion secured to a side of the frame against the inner face thereof,
- 20 and a flat plate part extending at an angle to said first mentioned portion and provided with a depending ear portion disposed in a plane substantially at right angles to the first mentioned flat plate portion and in-

wardly of the position of the legs when folded, each brace being connected with one of the legs and to the depending ear portion of one of the bracket members.

6. A table including a top, a frame for supporting the top, a reinforcing strip for the top secured thereto and extending across the same inwardly of the top supporting frame, legs pivoted to the top supporting frame to fold within the same, and leg attaching and top supporting means comprising a bolt or 35 the like engaging an opening in the top supporting frame and supported by said frame, said bolt extending inwardly of the frame through an opening in one of the legs and forming a pivot therefor, and an inwardly 40 extending supporting portion on the bolt extending in the vertical plane thereof and underlying an end portion of said reinforcing strip to sustain the latter.

In testimony whereof I hereunto affix my 45 signature.

ERNEST E. GOWELL.
